UNITED STATES PATENT OFFICE

RUFUS DUNN, OF WINCHESTER, KENTUCKY

SWITCH

Application filed July 15, 1929. Serial No. 378,478.

This invention relates to an electric switch adapted to be used with a door, the general object of the invention being to provide a rotary member having four projections thereon arranged a quarter turn from each other, with a pair of bridging strips on the member through which a pair of pins, the members of which are diametrically opposite each other, pass, whereby when an arm is engaged by a trip on a door which is being opened, the rotary member will be moved a quarter turn to place one of the contact strips in a position to bridge two members of a circuit so as to close the circuit, the trip being so constructed that the door can be closed without operating the member and then when the door is again opened, the member will be moved another quarter turn so as to break the circuit. Thus by opening the door the first time, the circuit is completed and when the door is opened the second time, the circuit is broken. The invention is useful for controlling the circuit of a lamp in a cellar where a person entering the cellar will open the door and close the circuit of the lamp, after which the door is closed. Then when the person leaves the cellar, as he opens the door the second time, the circuit is broken.

This invention also consists in certain other features of construction and in the combination and arrangement of the several parts, to be hereinafter fully described, illustrated in the accompanying drawings and specifically pointed out in the appended claim.

In describing the invention in detail, reference will be had to the accompanying drawings wherein like characters denote like or corresponding parts throughout the several views, and in which:

Figure 1 is a view partly in section, showing the switch member applied to the casing of a door and the trip on the door.

Figure 2 is a front view, with a part of the switch casing broken away.

Figure 3 is a side view looking in the opposite direction from Figure 1.

Figure 4 is a top plan view of the switch device, with the casing in section.

Figure 5 is a transverse section through the rotary member.

Figure 6 is a perspective view of one of the spring terminal members.

Figure 7 is a view of the spring for the rotary member.

Figure 8 is a perspective view of the trip and its supporting bracket.

In these views, the numeral 1 indicates a base of nonconducting material and 2 indicates a casing suitably attached to the base and having an opening 3 in its lower front part. A rotary member 4, of cylindrical shape, is rotatably supported in the casing by the brackets 5 which are fastened to the base, and this member 4 is also formed of non-conducting material. The rotary member carries four pins 6 which are arranged a quarter turn from each other and it also carries a pair of bridging strips 7 and 7' which are diametrically opposite each other and are embedded in the member, and two of the pins pass through these bridging members. The pins will pass through the opening 3 during the rotary movement of the member.

A star wheel 8 is attached to one of the pintles of the rotary member and is engaged by a spring 9 attached to the base, this spring and star wheel acting to frictionally hold the rotary member against movement and also acting to finish the movement of the member after it has been initially moved so that the member will always come to rest with two of the pins in a vertical position and the other two in a horizontal position.

A pair of spring contacts 10 is fastened to the base, with their free ends rounded, as shown at 11, and engaging the rotary member. These contacts are connected by the conductors 12 which form portion of a circuit for a lamp or the like. As will be seen, the parts are so arranged that when the rotary member is moved to a position with one of the bridging members uppermost, said bridging member will engage the rounded parts 11 of the contacts 10 and thus complete the circuit, but when the bridging members are in a horizontal plane, the contacts 10 engage the insulated body of the rotary member and thus the circuit is broken.

Figure 1 is a view partly in section, showing the switch member applied to the casing of a door and the trip on the door.

Figure 2 is a front view, with a part of the switch casing broken away.

Figure 3 is a side view looking in the opposite direction from Figure 1.

Figure 4 is a top plan view of the switch device, with the casing in section.

Figure 5 is a transverse section through the rotary member.

A bracket 13 is fastened to the door 14, member for imparting rotary movement to the base 1 being fastened to the frame 15, the cylindrical member when the movable and this bracket carries a pivoted trip 16 member is moved in one direction. which is so arranged that when the door is In testimony whereof I affix my signature. 5 opened, it will engage the depending pin RUFUS DUNN. 70 6, thus rotating the member 4 a quarter turn. When the door is closed, the trip will simply pivot on the bracket and not turn the member 4. The parts should be so arranged 10 that when the door is first opened and the rotary member turned a quarter turn, one of the bridging strips will be brought in engagement with the contacts 10 and thus close the circuit. Then, as before stated, 15 the door can be closed without breaking the circuit. When the door is opened a second time, the rotary member will be turned to a position where the bridging strip is moved out of engagement with the contacts 10 and 20 the circuit is broken. Thus upon the first opening of the door, the circuit is closed and when the door is opened a second time, the circuit is broken. As before stated, this device is useful on a cellar door and permits a 25 person to close the circuit of a lamp in the cellar when he first opens the door and then when he leaves the cellar and opens the door a second time, he will close the circuit so that there is no danger of one forgetting to 30 open the circuit of a lamp in the cellar when he leaves the same. Of course, the invention 95 can be used for other purposes.

Besides being useful for controlling the circuit of a lamp in a cellar, the invention 100 35 can be also used for controlling the circuit of a lamp in a bathroom, toilet or any other place where such invention would be useful.

It is thought from the foregoing description that the advantages and novel features 105 40 of the invention will be readily apparent.

It is to be understood that changes may be made in the construction and in the combination and arrangement of the several parts, provided that such changes fall within the 110 45 scope of the appended claim.

What I claim is:—

In combination with a stationary member and a movable member, a base connected with the stationary member, arms extending 115 50 from the base, a cylindrical member of non-conducting material rotatably supported by the arms, a pair of conductor strips embedded in the cylindrical member at diametrically opposite points thereon, pins passing through the strips into the cylindrical member, pins carried by the cylindrical member, and arranged a quarter turn from the other pins, a circuit, including a pair of contact 120 55 members, connected with the base and engaging the cylindrical member whereby said contacts will be bridged by the conductor strips during the rotation of the cylindrical member and a trip part on the movable member 125 60 for engaging the pins on the cylindrical 65
